UNITED STATES PATENT OFFICE

2,086,882

SEPARATOR

Gotthilf Seitz, Frankfort-on-the-Main, Germany,
assignor to International Precipitation Company,
Los Angeles, Calif., a corporation of California

Application February 21, 1936, Serial No. 65,067
In Germany March 1, 1935

4 Claims. (Cl. 183—92)

This invention relates to apparatus for the separation of dust or other suspended material from gases, and particularly to apparatus of the type comprising a plurality of closely associated cyclone separating elements connected at their upper ends to a common gas inlet chamber and a common gas outlet chamber, and connected at their lower ends to a common hopper or chamber for receiving and collecting the separated material.

The principal object of the invention is to provide an apparatus of this type, in which the group of associated cyclone elements, which are preferably connected together to form a single structural unit, may be quickly and easily separated from the common gas inlet and gas outlet chambers, or from the common material collecting chamber, to provide access to the interior of the apparatus, as for the purpose of cleaning, inspection, or repair.

According to my invention, the several parts of the apparatus which are to be separated from one another are normally detachably connected together, but are so mounted as to provide for relative vertical movement of said parts with respect to one another upon detachment of the connections therebetween, and means are provided for effecting such relative vertical movement for the purpose of separating one of said parts from an adjacent part.

The invention may be more fully described with reference to the accompanying drawings illustrating one embodiment thereof, in which:

Fig. 1 is a side elevation of an apparatus according to the invention;

Fig. 2 is a partly sectional elevation on line 2—2 in Fig. 1;

Fig. 3 is a horizontal section on line 3—3 in Fig. 1;

Fig. 4 is a view corresponding to Fig. 1, showing the common material collecting chamber separated from the cyclone separating elements; and

Fig. 5 is a similar view, showing the cyclone elements separated from the common gas inlet and gas outlet chambers.

The apparatus as a whole is shown as comprising three main parts, namely, a gas header unit 1, a multiple-cyclone separating unit 2, and a material collecting unit 3. As hereinafter described, the interior of the gas header unit is divided into a gas inlet chamber 4 at the lower portion thereof and a gas outlet chamber 5 at the upper portion thereof, said chambers being provided respectively with gas inlet and gas outlet connections 6 and 7. The sides of said header are en-

closed by walls 8, while the lower end thereof is open, for communication with the cyclone elements.

Said header unit is mounted upon a suitable supporting frame, which is shown as comprising vertical frame members 9 and horizontal frame members 11, 12, and 13. Said header may be secured to and supported upon the supporting frame in any suitable manner, as by means of supporting members 14 consisting of angle bars 10 or the like, rigidly connected to said header and to said supporting frame.

The multiple-cyclone separating unit 2 comprises a plurality of vertically elongated tubular cyclone elements 16 of circular cross-section and relatively small diameter, mounted directly below the gas inlet chamber 4 and connected together to form a single structural unit. Each of said tubular elements is shown as provided at its upper end with sloping side wall portions 17, forming a rectangular opening 18 at the upper end thereof, and the upper edges of the several elements are secured together in any suitable manner, as indicated at 19.

The assembled group of cyclone elements is normally supported as a unit, in position with the upper ends thereof communicating with the inlet chamber 4, and means are provided for normally connecting said cyclone unit to the gas header unit 1, while permitting said units to be quickly and easily disconnected from one another. For this purpose, quick-detachable connecting means such as "C-clamps" may be provided for securing the angle bar members 14, connected to the lower end of the gas header unit 1, to corresponding angle bar members 22 connected to the upper end of the cyclone unit 2 along each side thereof. In Fig. 2, I have shown one such C-clamp at 23, and it will be understood that any suitable number of such clamps may be provided at intervals along the several sides of the apparatus. A suitable gasket may be provided between the angle bars 14 and 22, to prevent leakage therebetween.

A gas outlet tube 26 extends centrally within the upper portion of each tubular cyclone element 16, as shown in Fig. 2. The external diameter of said outlet tubes is somewhat less than the internal diameter of the tubular cyclone elements, so as to provide annular gas inlet passages 27 therebetween, which communicate with the inlet chamber 4. The tubes 26, which serve as gas outlet passages for the respective cyclone elements 16, extend upwardly through the inlet chamber 4, and communicate at their upper ends 55

with the outlet chamber 5. The upper end portions of said outlet tubes may be formed similarly to the upper end portions of the tubular cyclone elements, as above described, and the upper edges thereof are connected together as shown at 28, and are also connected to the side walls 8 of the header unit 1, so as to remain connected with said header unit when the cyclone unit 2 is separated therefrom, as hereinafter described. The interconnected upper end portions of said gas outlet tubes serve to separate the gas inlet chamber 4 from the gas outlet chamber 5.

Means are provided for producing swirling movement of the gas passing from the inlet chamber 4 into the respective tubular cyclone elements 16. For this purpose, an annular series of helically inclined vanes 31 may be mounted in the annular passages between the lower end portions of the gas outlet ends 26 and the cyclone 20 elements, and said vanes are preferably mounted on said gas outlet tubes, as clearly shown in Fig. 5.

The several cyclone elements 16 open at their lower ends into the material collecting unit 3, as shown for example at 33, and the lower end portions of said elements are preferably tapered in a downward direction as indicated at 34, so that the openings 33 are of smaller diameter than the main portion of the cyclone elements, providing restricted centrally disposed dust outlet openings.

The material collecting unit 3 comprises a chamber or hopper preferably provided with downwardly and inwardly inclined side walls 35, and any suitable means may be provided for continuous or intermittent discharge of collected material through an opening at the bottom of said chamber as at 32.

A horizontal plate 36 secured to and around the lower ends of the cyclone elements 16 serves to normally close the upper end of the collecting chamber 3 and prevent communication of said chamber with the exterior, while permitting free communication of said chamber with the interior 45 of the cyclone units. Re-enforcing bars 39 may be provided at the edges of said plate 36. The material collecting unit 3 is also connected to the cyclone unit 2 by quick-detachable connecting means. For this purpose, I may provide angle bars 37 or the like, extending around the four 50 sides of the chamber 3 at the upper edge thereof, and any suitable number of quick-detachable connecting devices, such as C-clamps, may be provided for normally securing said angle bar against the lower face of the plate 36, one such 55 C-clamp being shown at 38 in Fig. 1. A suitable gasket may be provided between the members 37 and 36.

Means are provided for vertically raising and lowering the material collecting unit 3 alone, or the material collecting unit 3 and the cyclone separating unit 2, to provide access to the interior of the apparatus at the position of connection between any two of the three units 1, 2, and 3. The means for this purpose may advantageously 65 comprise a hoist device operatively associated with the units 2 and 3, such as a flexible chain or rope 41, secured to the material collecting unit 3 as shown at 42. From the point of connection 70 42, the chain 41 extends upwardly, over an idler sprocket or pulley 43, then downwardly over an actuating sprocket or drum 44, thence over an idler sprocket or pulley 45, and upwardly to the connection 42.

75 I prefer to provide two such hoist devices, one

at each side of the apparatus, as indicated in Fig. 2. To provide for simultaneous operation thereof, the two sprockets 44 which serve as drive sprockets for the chains 41, are shown as mounted upon a shaft 46, and a crank 47 is operatively connected to said shaft through worm gear means 48. It is understood that the particular form of hoisting means shown is merely illustrative, and that any other suitable means may be employed for vertically raising and lowering the material collecting unit 3 and/or the cyclone unit 2.

Means are preferably also provided for guiding and laterally positioning the units 2 and 3. For this purpose, I have shown four vertical guide rods 51 positioned adjacent the respective corners of the apparatus. Said guide rods may be secured at their upper ends to the fixed supporting bars 14, as shown at 52, and at their lower ends to diagonal frame members 53, which are secured to the lower horizontal frame members 13. It will be understood that the guide rods 51 extend through openings, not shown, in the angle bars 22 at the upper end of the cyclone unit 2, in the plate 36 and bars 39 at the lower end of said unit and in the angle bars 37 at the upper end of the material collecting unit 3, the several members above mentioned slidably engaging said guide rods.

In the operation of the above apparatus, gas containing dust or other suspended material is introduced through inlet connection 6, and after separation of a substantial portion of the suspended material as hereinafter described, the clean gas is discharged through outlet connection 7, it being understood that the flow of gas through the apparatus at a suitable velocity may be maintained either by natural draft or by artificial draft, as through the agency of a fan.

The gas supplied to inlet connection 6 enters the gas inlet chamber 4 and passes downwardly through the annular passages 21 and between the inclined vanes 31 which impart thereto a rapid whirling motion about the axes of the respective cyclone elements 16. The gas thus entering each cyclone element passes downwardly therein with a whirling motion, and then inwardly and upwardly through the outlet tube 26 of that element. The suspended material, or a substantial portion thereof, is thrown outwardly by centrifugal force within the cyclone outlets, and is carried downwardly along the walls thereof, and discharged through the restricted dust outlet openings 33 into the material collecting chamber 3, where it is deposited and whence it may be removed either continually or from time to time through the outlet opening at 32, it being understood that suitable means are provided for normally preventing outflow or inflow of gas or air through said opening. The clean gas discharged through the outlet tubes 26 passes through the outlet chamber 5 to the outlet connection 7. The operation of the above described apparatus, for the separation and collection of suspended material, is substantially the same as that described in United States Patent No. 65 1,909,184, and reference may be had to said patent for a more complete description of such operation.

It frequently becomes desirable to gain access to the interior of the apparatus, for the purpose 70 of cleaning, inspection, repair, or replacement of parts. By disconnecting the C-clamps 38 or other connecting devices between the cyclone unit 2 and the material collecting unit 3, while leaving the cyclone unit secured to the gas header 75

unit 1, and operating the hoist chains 41, the material collecting unit 3 may be moved vertically downward away from the cyclone unit, to some such position as indicated in Fig. 4, permitting free access to the interior of the material collecting unit 3 and the lower end portions of the several cyclone elements 16, while by reversing these operations, the material collecting unit 3 may be returned to its original position and again connected to the cyclone unit 2.

On the other hand, by disconnecting the C-clamps 23 or other means normally connecting the cyclone unit 2 to the gas header unit 1, and preferably leaving the cyclone unit 2 and material collecting unit 3 connected together, and operating the hoist chains 41, the units 2 and 3 may be moved vertically downward away from the gas header unit 1, to some such position as indicated in Fig. 5, permitting access to the upper portions of the cyclone elements 16, to the means 31, and to the inside and outside of the outlet tubes 26, as well as to the inlet chamber 4. In this case also, the parts may be restored to their normal position by reversing the above operations.

It will be observed that the hoist chains serve to support the weight of the detached unit or units in any desired position, and that, in the particular construction shown, the same hoist mechanism serves to effect the vertical closing and opening movements of either the unit 3 alone or the units 2 and 3 together, according to whether one or both of said units is detached. It will be apparent, however, that separate operating means might be employed for raising and lowering the respective units. Numerous other modifications may also be made, in the construction and arrangement of the several parts of the apparatus, without departing from the spirit of this invention as defined in the appended claims.

I claim:

1. An apparatus for separating suspended material from gases comprising: a gas header unit provided with separate gas inlet and gas outlet chambers; a separating unit disposed below said gas header unit and detachably connected thereto and comprising a plurality of tubular cyclone separating elements, each provided at its upper end with a gas passage communicating with said gas inlet chamber, and each provided at its lower end with a restricted outlet opening for separated material; a gas outlet passage positioned in the upper portion of each of said separating elements, supported by said gas header unit and communicating with the gas outlet chamber thereof; a material collecting chamber disposed below said separating unit and communicating with said restricted outlet openings of said separating elements; and means operatively associated with said separating unit and operable to raise and lower the cyclone separating elements vertically toward and away from said gas header unit when said units are detached from one another so as to expose the lower portion of said gas header unit and said gas outlet passages.

2. An apparatus as set forth in claim 1, in which the gas outlet passages for said cyclone separating elements comprise tubular members secured to said gas header unit and communicat-

ing at their upper ends with said gas outlet chamber and extending concentrically within the upper portions of the respective separating elements, and in which the annular passages between said tubular members and the upper portions of the respective separating elements constitute the gas inlet passages for said separating elements, said apparatus including a plurality of inclined vanes disposed within said gas inlet passages for imparting whirling motion to the gas passing therethrough.

3. An apparatus for separating suspended material from gases comprising: a gas header unit provided with separate gas inlet and gas outlet chambers; a separating unit disposed below said gas header unit and comprising a plurality of tubular cyclone separating elements, each provided at its upper end with a gas inlet passage communicating with said gas inlet chamber, and each provided at its lower end with a restricted outlet opening for separated material; a gas outlet passage positioned in the upper portion of each of said separating elements supported by said gas header unit and communicating with the gas outlet chamber thereof; a material collecting chamber disposed below said separating unit and detachably connected thereto and communicating with said restricted outlet openings of said separating elements; and means operatively associated with said material collecting chamber and operable to raise and lower the same vertically toward and away from said separating unit when said collecting chamber is detached from said separating unit so as to expose the outlet openings of said separating elements.

4. An apparatus for separating suspended material from gases comprising: a gas header unit provided with separate gas inlet and gas outlet chambers; a separating unit disposed below said gas header unit and detachably connected thereto and comprising a plurality of tubular cyclone separating elements, each provided at its upper end with a gas inlet passage communicating with said gas inlet chamber, and each provided at its lower end with a restricted outlet opening for separated material; a gas outlet passage positioned in the upper portion of each of said separating elements supported by said gas header unit and communicating with the gas outlet chamber thereof; a material collecting chamber disposed below said separating unit and detachably connected thereto and communicating with said restricted outlet openings of said separating elements; and hoist means operatively connected to said collecting chamber and operable to vertically raise and lower the same, whereby, upon detachment of said collecting chamber from said separating unit, said hoist means is operable to raise and lower said collecting chamber toward and away from said separating unit so as to expose the outlet openings of said separating elements and, upon detachment of said separating unit from said gas header unit, said hoist means is operable to raise and lower the cyclone elements of said separating unit, together with the collecting chamber, toward and away from said gas header unit so as to expose the lower portion of said gas header unit and said outlet passages.
